UNITED STATES PATENT OFFICE.

ALBERT G. DAVIS, OF SCHENECTADY, NEW YORK, ASSIGNOR TO GENERAL ELECTRIC COMPANY, A CORPORATION OF NEW YORK.

BLOCK-SIGNAL SYSTEM.

No. 927,404.

Specification of Letters Patent.

Patented July 6, 1908.

Application filed March 28, 1906. Serial No. 308,432.

To all whom it may concern:

Be it known that I, ALBERT G. DAVIS, a citizen of the United States, residing at Schenectady, county of Schenectady, State of New York, have invented certain new and useful Improvements in Block-Signal Systems, of which the following is a specification.

My invention relates to block signal systems for electrically-operated roads employing the rails for the return conductor for the power-current. Such roads have been installed heretofore with the rails properly sectioned to form blocks for the signal-current, and with connections between the blocks adapted to transmit the power-current but so arranged as to prevent the flow of signal-current from one block to another. Such an arrangement is easily secured for a single track, but it sometimes happens in the case of roads having parallel tracks that it is desirable to cross-connect the two or more tracks so as to improve the conductivity of the system for the power-current. For instance, if the resistance of the rail-circuit of a block is high, owing to defective bonding, this will introduce a loss in the power-circuit if the tracks are not cross-connected, but with the cross-connections, the other tracks serve as a low-resistance shunt for the defective rail-circuit. When such cross-connections are employed, however, a difficulty is introduced in guarding against broken rails. Since the rails of one block are shunted by the rails of the parallel block or blocks, a broken rail will not open the signal-circuit, and consequently, with a system as ordinarily arranged, the signal for a block may indicate "clear" in spite of a broken rail in the block. This is obviously a source of danger, and the object of my invention is to reduce the possibility of accident from this cause.

My invention in one aspect consists in inserting a winding between each rail of a block and the cross-connection from the other track, and providing means for putting the signal for that block at "danger" upon the failure of current in either winding. Obviously, if there is a break in either rail, one of the two windings must be open-circuited; and by so arranging the signal apparatus that the signal is put at danger upon the failure of current in either winding, absolute protec-

tion is secured. It has been proposed heretofore in the case of direct-current roads to employ alternating-current for the signal-circuits, since by so doing interference between the power and signal-currents may readily be avoided.

My invention, as applied to roads having alternating-current signal systems, further comprises arranging the windings between the cross-connection from the other track to the rails of the block, as primary transformer windings, and so arranging the second transformer windings and the relays supplied therefrom that the signal is put at "danger" when either primary transformer winding is deenergized.

Still more specifically, my invention consists in placing both primary transformer windings on the same magnet core, and so arranging the core that a portion of it is traversed by an alternating flux only upon an unbalancing of the alternating signal current in the two primary windings, and providing a secondary winding on that portion of the magnetic circuit with means supplied from the secondary winding for putting the signal at "danger".

My invention will best be understood by reference to the accompanying drawing, which shows diagrammatically a block signal system arranged in accordance with my invention.

I have illustrated and shall describe my invention as applied to a road employing alternating-current for the signal circuits, but it will be understood that in its broader aspect my invention is not limited to an alternating-current system.

In the drawing, A A' represent the rails of two parallel blocks of an electrically-operated road.

B B' represent supply conductors for the power-current, either third rails or trolley wires. The rail-circuit of the block A is supplied with alternating-current by a transformer C, the secondary of which is connected across the rails and the primary of which is connected to the alternating-current line-wires D.

E represents a magnetic core, which is placed at the signal-end of the block and comprises an E-shaped member and a magnetic member e opposite the three limbs of the E-shaped member, but separated from

each of the limbs by an air-gap. Two coils F F are placed on the two outer limbs of the E-shaped member and are connected in series across the rails A. These coils are so wound that the alternating signal current passing through them produces a flux which passes in series through the two coils and through the member e. With equal currents flowing through the two windings F the middle limb of the E-shaped member is not traversed by any alternating flux. Secondary windings f f are placed in inductive relation to the windings F F and supply a coil G of the track relay. This relay is shown as of the two-phase induction type, since this form of relay is not affected by an unbalanced fluctuating power-current in the windings F F. The other primary coil H of the relay is supplied directly or through a transformer from the alternating-current line-wires D. The short-circuited secondary member of the relay carries a contact which, when both primary relay coils are energized, closes a circuit through the source of current I and the operating mechanism J of the signal K. This operating mechanism is merely indicated diagrammatically, and may be of any well-known type.

It will be seen that the point of connection between the two coils F F is connected to the central point of the secondary winding of the transformer supplying the adjacent block of the same track, and also to the opposite track. This connection is made of sufficient cross-section to carry the power-current, as are also the transformer windings connected to the track. The power-current coming from the adjacent block of the same track, or from the opposite track, normally divides substantially equally between the coils F F, passing through the rails A in parallel. The magnetomotive forces due to this current in the coils F F oppose each other in the member e and assist each other in magnetizing the central limb of the E-shaped member. The air-gaps between the E-shaped member and the member e are for the purpose of preventing saturation of the core by the power-current.

With a system as thus far described, it will be seen that a break in one of the rails A, as, for instance, at X, may not cause the signal K to indicate danger, since current will flow from the central point of the secondary of transformer C through the cross-connection to the opposite block through the windings F' F' in parallel, through the rails A' in parallel, through the two portions of the secondary winding of transformer C' in opposite directions, to the cross-connection, thence through the right-hand coil F and through the lower rail A to the right-hand terminal of the secondary of transformer C. This current in the winding F may be sufficient to energize the secondary winding f, and

through it the relay coil G, so as to hold the relay in clear position. Obviously, this is a source of serious danger.

In order to prevent the signal K from giving a clear indication with a broken rail in the block A, I place a secondary coil L on the middle limb of the E-shaped member and connect to this secondary a winding M of another relay, the contacts of which are normally closed, and are included in the signal-operating mechanism. This signal is also shown as of the polyphase induction type, having a second winding N supplied from the line-wires D, so that fluctuations of the flux produced by the power-current in the central limb of the magnetic member E will not operate the relay. It will be seen that with current flowing through only one of the windings F, as, for instance, the right-hand winding, as would be the case if a rail were broken at X, the alternating flux due to the current in the right-hand winding F will divide between the left-hand central limbs of the member E. This flux will consequently energize the relay winding M so as to actuate the relay to open the signal-circuit. This actuation of the relay will occur upon the de-energizing of either of the coils F, so that a break in either rail of the block A will produce a danger indication of the signal.

I do not desire to limit myself to the particular construction and arrangement of parts here shown, but aim in the appended claims to cover all modifications which are within the scope of my invention.

What I claim as new and desire to secure by Letters Patent of the United States, is:

1. In a signal system for electrically-operated roads having parallel tracks, a connection from a block to the parallel track adapted to form a path for the power-current, two windings inserted respectively between the rails of the block and said connection, a signal for said block, and means operative upon the failure of current in either winding for causing said signal to indicate "danger".

2. In a signal system for electrically-operated roads having parallel tracks, a connection from a block to the parallel track adapted to form a path for the power-current, two windings inserted respectively between the rails of the block and said connection, a signal for said block, electric operating mechanism therefor, and means operative upon the failure of current in either of said windings for breaking the circuit of said operating mechanism.

3. In a signal system for electrically-operated roads having parallel tracks, a connection from a block to the parallel track adapted to form a path for the power-current, two windings inserted respectively between the rails of the block and said connection, a signal for said block, electric operating mechanism therefor, and relay contacts in circuit with

said operating mechanism controlled by the current in said windings and arranged to break the circuit of said operating mechanism upon the failure of current in either 5 winding.

4. In a signal system for electrically-operated roads having parallel tracks, means for supplying alternating-current to the rail-circuit of a block, a connection from the 10 block to the opposite track adapted to form a path for the power-current, two inductive windings inserted respectively between the rails of said block and said connection, a signal for said block, and means operative 15 upon the failure of current in either of said windings for causing said signal to indicate "danger".

5. In a signal system for electrically-operated roads having parallel tracks, means 20 for supplying alternating-current to the rail-circuit of a block, a connection from the block to the opposite track adapted to form a path for the power-current, two primary transformer windings inserted respectively 25 between the rails of the block and said connection, secondary windings inductively related to said primary windings, relays supplied from said secondary windings, and a signal controlled by said relays, said secondary 30 windings and relays being arranged to cause said signal to indicate "danger" upon the failure of current in either primary winding.

6. In a signal system for electrically-operated roads having parallel tracks, means 35 for supplying alternating-current to the rail-circuit of a block, a connection from the block to the opposite track adapted to form a path for the power-current, a magnetic circuit, two windings on said magnetic circuit inserted respectively between the rails of the block and said connection and arranged to produce a change of flux distribution in said magnetic circuit upon a failure 40 of current in either winding, a signal for the block, and means responsive to said change of current in either winding for causing the signal to indicate "danger".

7. In a signal system for electrically-operated roads having parallel tracks, means for 50 supplying alternating-current to the rail-circuit of a block, a connection from the block to the opposite track adapted to form a path for the power-current, a magnetic circuit, two windings on said magnetic circuit inserted 55 respectively between the rails of the block and said connection and arranged to produce a change of flux distribution in said magnetic circuit upon a failure of current in either 60 winding, secondary windings on said magnetic circuit, relays supplied from said secondary windings, and a signal for the block controlled by said relays, said secondary windings and said relays being arranged to 65 cause the signal to indicate "danger" upon

a change in flux distribution in said magnetic circuit.

8. In a signal system for electrically-operated roads having parallel tracks, means for supplying alternating-current to the rail-circuit of a block, a connection from the block to the opposite track adapted to form a path for the power-current, two windings inserted respectively between the rails of the block and said connection, a magnetic circuit 70 for said windings having a portion traversed by an alternating flux only upon an unbalancing of the alternating-current in said windings, a secondary winding carried on said portion of the magnetic circuit, a signal 75 for the block, and means for causing said signal to indicate "danger" upon a flow of current in said secondary winding.

9. In a signal system for electrically-operated roads having parallel tracks, means for 80 supplying alternating-current to the rail-circuit of a block, a connection from the block to the opposite track adapted to form a path for the power-current, two windings inserted respectively between the rails of the 85 block and said connection, a magnetic circuit for said windings having a portion traversed by an alternating flux only upon an unbalancing of the alternating-current in said windings, a secondary winding carried on said portion of the magnetic circuit, a signal 90 for the block, and a relay connected to said secondary winding and controlling said signal.

10. In a signal system for electrically-operated roads having parallel tracks, means for 100 supplying alternating-current to the rail-circuit of a block, a connection from the block to the opposite track adapted to form a path for the power-current, two windings 105 inserted respectively between the rails of the block and said connection, a magnetic circuit for said windings having a portion traversed by an alternating flux only upon an unbalancing of the alternating-current 110 in said windings, a secondary winding carried on said portion of the magnetic circuit, a signal for the block, and a relay coil connected to said secondary winding and arranged when energized to cause said signal 115 to indicate "danger".

11. In a signal system for electrically-operated roads having parallel tracks, a connection from a block to the opposite track adapted to form a path for the power-current, two windings inserted respectively between the rails of the block and said connection, a magnetic circuit for said windings having a portion traversed by a flux due to the current in said windings only upon an 120 unbalancing of said current in said windings, a signal for the block, and means responsive to the flux in said portion for causing the signal to indicate "danger".

12. In an alternating-current signal sys- 130

tem, a source of alternating-current connected to the rails of a block, two windings connected in series across said rails, a signal for the block, and means for causing said signal to indicate "danger" upon an unbalancing of the alternating-current in said windings.

13. In an alternating-current signal system, a source of alternating-current connected to the rails of a block, a transformer having two primary windings connected across said rails, a signal for the block, and means for causing the signal to indicate "danger" upon an unbalancing of the alternating-current in said windings.
14. In an alternating-current signal sys-

tem, a source of alternating-current connected to the rails of a block, a transformer having two primary windings connected across said rails, a magnetic circuit for said windings having a portion traversed by a flux due to the current in said windings only upon an unbalancing of said current in said windings, a signal for the block, and means responsive to the flux in said portion for causing the signal to indicate "danger".

In witness whereof, I have hereunto set my hand this 26th day of March, 1906.

ALBERT G. DAVIS.
